UNITED STATES PATENT OFFICE

170,633

PORTABLE PROJECTOR

Harold G. Fitz Gerald, Los Angeles, Calif.

Application December 22, 1952, Serial No. 22,818

Term of patent 14 years

(Cl. D61—1)

To all whom it may concern:

Be it known that I, Harold G. Fitz Gerald, a citizen of the United States, residing at Los Angeles, in the county of Los Angeles and State of California, have invented a new, original, and ornamental Design for a Portable Projector, of which the following is a specification, reference being had to the accompanying drawings, forming a part thereof.

Fig. 1 is a top perspective view of a portable projector showing my new design. Fig. 2 is a bottom perspective view which shows the side opposite that shown in Fig. 1. Fig. 3 is a perspective view showing the device in open position for use, and Fig. 4 is a similar view showing the side opposite Fig. 3.

I claim:

The ornamental design for a portable projector, as shown.

HAROLD G. FITZ GERALD.
